UNITED STATES PATENT OFFICE.

JONATHAN CREAGER, OF CINCINNATI, OHIO, ASSIGNOR OF ONE-HALF TO
WILHELM PIEPER, OF SAME PLACE.

BRICK-MACHINE.

SPECIFICATION forming part of Letters Patent No. 257,665, dated May 9, 1882.

Application filed February 24, 1882. (No model.)

To all whom it may concern:

Be it known that I, JONATHAN CREAGER, a citizen of the United States, residing at Cincinnati, in the county of Hamilton and State of Ohio, have invented certain new and useful Improvements in Brick-Machines, of which the following is a specification.

My invention comprises a novel construction of bumper or jarring apparatus for uniformly loosening compressed clay in brick-machine molds, and without destroying or impairing the symmetrical shape of the unburned bricks, as hereinafter more fully described, and pointed out in the claims.

15 In the annexed drawings, Figure 1 is a plan of my bumper. Fig. 2 is a vertical section of the same, taken in the plane of one of the bearing-bars. Fig. 3 is a vertical section of the apparatus, taken transversely of the delivery-frame, a mold being shown supported on the bearing-bars. Fig. 4 is an elevation of the striker and its attached knife. Fig. 5 is a horizontal section through one end of the same. Figs. 6 and 7 are detail views of the leveling 25 keys or wedges.

A A' represent the side beams, and B B' B" the cross-beams, of the delivery-frame of a brick-machine of any approved construction, said frame being so arranged as to allow the 30 ejected molds to travel in the direction of the arrow seen in Fig. 1. The beams A A' are cut away on top, at a a' respectively, to receive the bumper, jar, or agitator, which device consists of two parallel beams, C C', disposed 35 transversely with reference to said sides A A', and secured at either end by boards D E, said boards having attached to them blocks d d' e e', united by rounds or handles F F'.

G are bearing-bars attached to the cross-beams of the frame, and so arranged as to allow free play beneath them of the jar or bumping device.

Secured to the end beam, B, are stops H H', so arranged as to arrest the mold I in a perfectly square position with reference to the bumping apparatus, as indicated by the dotted lines in Fig. 1. The bumper travels on rollers j j', secured to bearers J J', fastened to the side beams, A A'.

K represents a portion of a plate secured to 50 the press-box, and L is the striker, having racks l l', wherewith it is raised and lowered in the usual manner by means of pinions engaging with said racks. In order to cause this striker to act uniformly along the entire 55 upper face of the mold, and thereby scrape all superfluous clay from off the same, said striker is provided with two set-screws, N N', as seen in Fig. 4. After the striker has once been lowered and properly adjusted to the exact 60 level of the mold, these screws or bolts are tightened up, so as to secure this plate L immovably in position. I prefer, however, to arm the lower edge of the striker with a readily-detachable knife, O, that can be removed 65 and reground whenever it becomes dulled by constant use, or in case it should be broken. This knife is secured to the striker with screws o, having countersunk heads presented toward the press-box of the machine.

Referring to Figs. 6 and 7, P represents one of the sills of the machine, said sill being notched at p to receive a vertically-acting key or wedge, R, upon which rests one of the side beams, A. Furthermore, this sill has a seat, 75 p', for the reception of a horizontally-acting key or wedge, R', adapted to bear against the key R. In case the frame A A' B B' should be too low, the wedge R can be driven in until the proper elevation has been obtained, and 80 then the key R' is driven home. By this arrangement the key R will be preserved from working loose, no matter how roughly the machine may be used.

The operation of my bumping apparatus is 85 as follows: As the charged mold emerges from the press-box of the machine the superfluous clay is scraped off perfectly level by the knife O and the mold is run back on the bearing-bars G, either automatically or by hand, until 90 it comes in contact with the stops H H', as indicated by dotted lines in Fig. 1. The mold now stands at right angles to the frame, and the operator, grasping the handles F F', proceeds to reciprocate the bumper, so as to cause it to strike alternately the opposite ends of said mold, the blocks d d' e e' serving to impart momentum to the apparatus and compel-

ling it to give a sharp quick blow that loosens the compressed clay in the most thorough and uniform manner. Owing to the location of the stops $H H'$, the blocks $d d' e e'$ strike squarely 5 against the opposite ends of the mold, thereby preventing the clay being twisted out of its proper shape or being enlarged and thickened at the ends and corners, which defects would occur in case the blows were delivered 10 obliquely against the mold. Therefore the clay when dumped out of the mold will be symmetrical in shape, with the corners perfectly sharp and square.

If desired, the bumping-faces of the blocks 15 at the ends of the jarring apparatus may be protected with leather or rubber or other elastic cushions, as seen at $S S'$ in Fig. 3.

Instead of the bars G , other suitable devices may be employed for supporting the mold 20 and allowing free play of the bumper.

I claim as my invention—

1. A bumping apparatus reciprocating transversely of the delivery-frame of a brick-ma-

chine, and adapted to alternately strike the opposite ends of the charged molds, in combination with suitable stops for arresting said molds in a proper position, substantially as described.

2. The combination, in a brick-machine, of delivery-frame $A a A' a'$, reciprocating bumper $C C' D E$, bearing-bars G , and stops $H H'$, substantially as described.

3. A brick-machine bumper consisting of the beams $C C'$, ends $D E$, blocks $d d' e e'$, and handles $F F'$, as and for the purpose specified.

4. The bumper $C C' D d' F E e e' F'$, mounted on rollers $j j'$, and reciprocating transversely of the delivery-frame of a brick-machine, substantially as herein described.

In testimony whereof I affix my signature in presence of two witnesses.

JONATHAN CREAGER.
